UNITED STATES PATENT OFFICE.

JAMES R. MANRY, OF PORTALES, NEW MEXICO.

PUMP.

Application filed January 30, 1923. Serial No. 615,876.

To all whom it may concern:

Be it known that I, JAMES R. MANRY, a citizen of the United States, residing at Portales, in the county of Roosevelt and State of New Mexico, have invented certain new and useful Improvements in Pumps; and I do hereby declare the following to be a full, clear, and exact description of the invention, such as will enable others skilled in the art to which it appertains to make and use the same.

The invention relates to the type of pump embodying a wheel over which passes a chain or analogous part provided at intervals in its length with blocks which operate to displace the water in a well, when the pump is in operation.

In accordance with the present invention, the wheel is adapted to be oscillated to impart a reciprocating movement to the flexible connection provided with the blocks, a casing being provided for each end portion of the flexible connection and each casing having a foot valve for retaining the column of water therein and preventing the escape of the same through the bottom of the casing on the down stroke of the end portion of the flexible connection.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application,

Figure 1 is a front view of a pump embodying the invention,

Figure 2 is a side view thereof, parts being broken away,

Figure 3 is a detail view of a portion of the flexible connection to which the blocks or displacing elements are attached, and

Figure 4 is a sectional view of one of the blocks or displacement elements showing the manner of attaching the blocks or displacement elements to the chain.

Corresponding and like parts are referred to in the following description and designated in the several views of the drawings by like reference characters.

In the accompanying drawings, the numeral 1 designates a horizontally disposed shaft mounted at its ends in suitable bearings 2. A wheel 3 is fast to the shaft 1 and a chain 4 or analogous flexible connection passes over the wheel 3 and is supported thereby. Blocks or other displacement elements 5 are secured to the chain at intervals in its length and operate to displace and thereby elevate water from a well or other source of supply. One side of each of the blocks of the displacement element is provided with a longitudinal groove 5' which is deep enough to receive substantially two-thirds of the chain leaving a portion thereof to extend beyond the side of the blocks or displacement elements, in order that the chain may bear against the wheel and prevent the blocks or elements from becoming worn. The wells are provided with casings 6 which are disposed in line with the opposite sides of the wheel 3 and are adapted to receive end portions of the chain or flexible connection 4. A foot valve 7 is provided at the lower end of each of the casings 6 to confine the column of water therein. The flexible connection 4 including the blocks or displacement elements 5 is of sufficient weight to submerge itself in the column of water contained in the casing and thereby displace the same, or if found more convenient sufficient weights may be added to the flexible elements to cause the same to submerge.

The wheel 3 has its periphery concaved, and provided with sprocket teeth 8 adapted to engage the chain 4 and operate the same, and the displacing elements or blocks 5 are circular in horizontal cross section and are adapted to partly fit within the concaved surface of the wheel. The casings 6 are circular in horizontal cross section and are adapted to receive the blocks or displacing elements 5.

In the practical operation of the pump, the wheel 3 is adapted to have a reverse rotary movement imparted thereto, whereby the flexible connection 4 carrying the blocks or displacing elements 5 is engaged by the teeth 8 and reciprocated in the casings 6 so as to effect a displacement of water therein, which water will be discharged at the upper end of the casing. The casings 6 are of slightly larger diameter than are the blocks or displacement elements 5, so as to provide a space between the peripheries of the blocks or displacing elements and the inner periph-

ery of the casing. Upon the upstroke of the flexible connection carrying the blocks or displacing elements 5 in one of the casings 6, water is drawn into the casing through 5 the foot valve 7. The opposite end of the flexible connection 4 moves downwardly through the column of water supported in the opposite casing by the foot valve 7, and the water in the casing in which the flexible 10 connection is moving downwardly is prevented from escaping at the bottom of the casing and being displaced by the blocks 5 is forced around the blocks and between the blocks and the inner walls of the casing and 15 discharged at the upper end of the casing. On reverse movement of the pump, the operation previously described is reversed and the end portion of the flexible element which previously moved up is moved down to dis- 20 place the water in its casing 6 and discharge the same at the top of the casing, and the end of the flexible connection which previously moved downward and displaced the water is moved upward and draws water

into its casing through the foot valve 7. It 25 is of course to be understood that the foot valve 7 is of the one-way type. It will thus be understood that water is alternately dis- charged from the casings 6.

Having thus described the invention, 30 what I claim is:—

A pump of the character specified, comprising a wheel, a flexible connection passing over the wheel and supported thereby, blocks provided with grooves and secured at intervals to said flexible connections, casings in line with the opposite sides of the wheel and adapted to receive end portions of the flexible connections together with the blocks, and foot valves at the lower 35 ends of the casings for supporting columns 40 of water therein.

In testimony whereof I affix my signature in presence of two witnesses.

JAMES R. MANRY.
